H. S. GRISWOLD.
TOY VEHICLE.
FILED NOV. 26, 1921.

1,441,918.

UNITED STATES PATENT OFFICE.

HARVEY S. GRISWOLD, OF PONTIAC, MICHIGAN.

TOY VEHICLE.

Application filed November 26, 1921. Serial No. 518,027.

To all whom it may concern:

Be it known that I, HARVEY S. GRISWOLD, a citizen of the United States, residing at Pontiac, in the county of Oakland and State of Michigan, have invented certain new and useful Improvements in Toy Vehicles, of which the following is a specification.

This invention relates to toy vehicles, and it comprises a frame having wheels mounted thereon, a seat pivotally mounted on said frame, an axle having a crank portion, and a link connecting the crank portion of the axle and the seat.

An object of the present invention is the provision of a child's toy vehicle of simple construction and light weight, which is sufficiently strong to stand the wear and tear to which it is subjected.

A further object is the provision of a toy vehicle of this type in which the seat is mounted in brackets carried by the frame and is adjustable in said brackets to vary the distance between the seat and the frame, the link being correspondingly adjustable.

In the accompanying drawings, I have shown one embodiment of the invention. In this showing:

Figure 1 is a side elevation,

Figure 2 is a top plan view,

Figure 3 is a transverse sectional view on line 3—3 of Figure 2,

Figure 4 is a front elevation, and,

Figure 5 is a detail view of the front fork supporting member.

Referring to the drawings, the reference numeral 1 designates the side bars of the frame which are spaced from each other at the rear of the vehicle, and converge forwardly. These side bars are provided with bearing members 2 at their rear ends for the reception of a rear axle 3. Wheels 4 are secured to this axle in any suitable manner, and revolve therewith. The front ends of the side members are arranged parallel to each other, and are slightly spaced for the reception of arms 5, carried by a sleeve 6. The ends of the side bars are provided with openings adapted to a line with opening 7 in the arms 5 through which suitable bolts or other fastening members are passed to retain the parts in assembled position. A front fork 8 is provided with an arm extending through the sleeve 6 and a nut 9 is arranged on the outer end of this arm to retain the fork in position. A front wheel

10 is mounted in this fork. Suitable foot rests 11 are arranged on each side of the fork.

The vehicle is provided with a seat 12, comprising a substantially flat plate enlarged at the rear, as shown in Figure 2 of the drawings. A second plate 13 extends upwardly from the plate 12, adjacent the front, and this plate may be formed in the shape of a horse's head or other suitable character.

Suitable hand grips 14 are arranged on the vertical plate 13, and in the present showing, these hand grips form the horse's ears. The seat is provided with a pair of bracket members 15, arranged on opposite sides intermediate the front and rear and these bracket members are adapted to be pivotally received in an arm 16 of a bracket having an arm 17 which is secured to the side bars. As shown, the arm 16 is formed in two sections, each of which is provided with a plurality of openings 18 for the reception of bolts 19.

By varying the position of the bolts, the distance between the seat and the frame may be changed. The horizontal arm 17 of the bracket is provided with openings adapted to register with openings in the side bar for the reception of bolts 20.

The rear of the seat is provided with an extended portion 21 adapted to receive an upper portion 22 of a link. The link is further provided with a lower portion 23, the end of which is formed into a bearing member 24, adapted to be arranged over a crank portion 25 of the rear axle. The two sections of the link are each provided with a plurality of openings 26 for the reception of bolts 27. By varying the position of the bolts, the link may be adjusted when the position of the seat is adjusted.

In operation, the rider sits upon the rear portion of the seat, places his feet upon the foot rests 11, and grasps the hand grips 14. By rocking the body back and forth, the seat is oscillated on its pivot and the movement of the seat is transmitted to the rear axle 3, through the link sections 22 and 23, and the crank portion 25. This movement propels the vehicle. By providing an adjustable seat, the vehicle may be used by children of different ages and sizes, and may be adjusted from time to time as the child becomes larger.

The construction is very simple, eliminat-

110

5 ing all unnecessary parts between the frame and the seat and at the same time retaining the necessary strength.

It is to be understood that the form of the invention herewith shown and described is 10 to be taken as a preferred example of the same, and that various changes in the shape, size, and arrangement of parts may be resorted to without departing from the spirit of the invention or the scope of the subjoined 15 claims.

I claim:

1. A toy vehicle comprising a frame, a rear axle carried by said frame, said axle being provided with a crank portion, a seat 20 disposed above said frame, brackets connecting said seat and said frame, each of said brackets comprising a pair of arms, one of which is secured to the frame and the other of which pivotally supports the seat, 25 said arms being adjustable with respect to each other, and an adjustable link connecting the seat and the crank portion of the rear axle.
2. A toy vehicle comprising a frame, a

wheel mounted at one end of said frame, an axle mounted at the opposite end of said frame, said axle being provided with a crank, wheels carried by said axle, an elongated seat mounted above said frame, 30 said seat being provided intermediate its ends with integral down-turned ears and an integral extension at one end, a pair of brackets, each of said brackets comprising an upper vertical section pivotally 35 connected at its upper end to one of said ears and a lower L-shaped section having a vertical arm adjustably secured to the upper section and a horizontal arm secured to said frame, and a link 40 pivotally connected with said crank and the extension on said seat, said link being formed of a pair of adjustable sections.

In testimony whereof I affix my signature in presence of two witnesses.

HARVEY S. GRISWOLD.
